(57) **CLAIM**

The ornamental design for a tire for automobile, as shown and described.

DESCRIPTION

1. Tire for automobile

1.1 is a front elevation view of a tire for automobile showing my new design;

1.2 is a rear elevation view thereof;

1.3 is a top plan view thereof;

1.4 is a bottom plan view thereof;

1.5 is a right side elevation view thereof;

1.6 is a left side elevation view thereof;

1.7 is a perspective view thereof; and

1.8 is an enlarged partial front elevation view thereof, wherein the enlargement area is indicated by the broken line bracket marked 1.8 in 1.1.

The ghosted or low contrasted showing of portions of the tire for automobile do not form part of the claimed design.
